UNITED STATES PATENT OFFICE.

HERMAN DOCK, OF WYNCOTE, PENNSYLVANIA, ASSIGNOR TO THE DOCK GAS ENGINE COMPANY, OF NEW YORK, N. Y., A CORPORATION OF NEW JERSEY.

INTERNAL-COMBUSTION ENGINE.

No. 868,765.

Specification of Letters Patent.

Patented Oct. 22, 1907.

Application filed November 19, 1906. Serial No. 343,949

To all whom it may concern:

Be it known that I, HERMAN DOCK, a citizen of the United States, residing at Wyncote, Montgomery county, Pennsylvania, have invented certain new and useful Improvements in Internal-Combustion Engines, of which the following is a full, clear, and exact description.

My invention relates to improvements in internal combustion engines and consists in means for controlling the speed of the same. This means is also useful in facilitating the starting of the engine.

In the accompanying drawings: Figure 1 conventionally illustrates in section a gas engine cylinder with my improvement shown in side elevation. Fig. 2 is a relatively enlarged cross-section view of my invention. Fig. 3 is a longitudinal section on a smaller scale than shown in Fig. 2. Fig. 4 is a plan view of the controlling member broken away at the ends.

A conventionally represents the cylinder of an ordinary gas engine of the four-cycle type; the piston, rod, main shaft, etc. not being shown.

B represents the usual inlet valve.

D represents the usual outlet or exhaust valve.

E is a regular exhaust cam mounted on shaft F, which may be driven in the usual way from the main engine shaft (not shown). The function of cam E is to open the exhaust valve on every other return or back stroke of the piston.

G is a supplemental exhaust cam opposite to cam E but in alinement, by which I mean in the same plane therewith. The nose of this cam G is arranged to be projected or retracted at will. The cam G is mounted in a recess in the body of cam E in such a manner that it may be drawn entirely back so as to be inactive or projected outwardly in a radial direction to any desired extent within its full range of action. It follows from the foregoing that when the cam G is projected outwardly it will operate on the exhaust valve D on the intermediate return strokes of the piston and hence, since these intermediate return strokes are compression strokes, it follows the degree of compression within the cylinder may be modified to any desired extent. For this reason the cam G is useful not only in starting the engine but also in controlling the speed of the engine while running. In starting the engine the cam G would preferably be projected to its extreme limit so that the minimum compression would occur. As shown, after the engine has started the cam G may be retracted, whereupon the engine will "pick up" speed.

In the particular form shown in the drawings the cam G has two rearwardly projecting side arms G' G' which form the body or frame of the cam G. These arms straddle the shaft F and which serve to guide and steady said cam in its excursion to and fro. These arms

are supported by the side walls of the cavity in which the cam is located. Within the shaft F, which is hollow, is a relief cam controlling shaft H, this shaft has a sliding movement to and fro in the hollow cam shaft F and makes a suitable engagement with the supplemental cam G so that by shifting its longitudinal position within shaft F the supplemental cam G may be projected to any desired extent. As shown, the controlling shaft H is longitudinally recessed, the bottom of said recess forming an incline. G² is a stud or projection on the cam G between the side arms G' G'. The end of said projection G² passes into shaft F and is supported upon the incline at the bottom of the recess in the shaft H, hence, when said shaft is moved to and fro the cam G will be moved radially. One simple and effective means for retracting the cam G may comprise a spring I located between the shaft F and a part of cam G. As shown, the side arms G' G' are brought together underneath shaft F and this spring I bears against the same so as to force the cam G back into its recess in the cam E when the shaft H is retracted. A pin J may be provided to support the spring I, which latter in the particular form shown is spiral.

K is the usual lever pivotally mounted at one end, the other end bearing under the stem of exhaust valve D.

The usual anti-friction roller L may be provided to prevent undue wear on the cams.

One decided advantage of locating the cam G in alinement with the cam E resides in the fact that there is no necessity for shifting the cam shaft longitudinally in order to relieve the compression. In some instances the valve operating levers are shifted laterally in order to permit a relief cam to come into operation, but by my improved construction this is avoided.

Another advantage which results from the locating of the relief cam in alinement with the main cam is that much space is economized since both cams can be comparatively narrow. The ease and economy of replacement of the relief cam in case the same should become unduly worn is another advantage resulting from this construction. In the usual construction it is necessary to procure an entirely new main and relief cam where replacement is required since such members are ordinarily made integral.

What I claim is:

1. In an internal combustion engine an exhaust valve controlling means including a cam shaft a main cam, an oppositely arranged secondary cam carried thereby and in alinement therewith and means for projecting and retracting said cam to move it into or out of an operative position said means including a longitudinally movable inner shaft passing through said secondary cam.

2. In an internal combustion engine an exhaust valve controlling means including a cam shaft a main cam, an oppositely arranged secondary cam carried thereby and in alinement therewith and means for projecting and retracting

ing said cam to move it into or out of an operative position and for holding the same at an intermediate position said means including a longitudinally movable inner shaft passing through said secondary cam.

- 5 3. In an internal combustion engine an exhaust valve controlling means, including a cam shaft a main cam, an oppositely arranged secondary cam carried thereby and in alinement therewith and means for projecting and retracting said cam to move it into or out of an operative position and for holding the same at any intermediate position said means including a longitudinally movable inner shaft passing through said secondary cam to project the same, and a spring to retract the same.

4. In an internal combustion engine an exhaust valve

controlling means including a main shaft a main cam, an 15 oppositely arranged secondary cam carried thereby and in alinement therewith and means for projecting and retracting said cam to move it into or out of an operative position, said means including a longitudinally moving inner shaft concentric with the cam shaft and operatively connected with the supplemental cam said inner shaft having a longitudinal inclined groove in its face, said secondary cam having a projection extending into said groove and bearing on the incline thereof. 20

HERMAN DOCK.
